UNITED STATES PATENT OFFICE.

ABRAHAM ROCKOWITZ, OF NEW YORK, N. Y.

HOSE-SUPPORTER.

1,072,872.

Specification of Letters Patent. Patented Sept. 9, 1913.

Application filed March 9, 1911. Serial No. 613,408.

To all whom it may concern:

Be it known that I, ABRAHAM ROCKOWITZ, a subject of the Czar of Russia, and resident of the city and State of New York, have 5 invented certain Improvements in Hose-Supporters, of which the following is a specification.

This invention relates to certain improvements in hose supporters, and more particularly in that class of such devices which are especially designed and adapted for ladies' wear, and the object of the invention is to provide a device of this character of a simple and comparatively inexpensive 15 nature having certain features of novelty and improvement, whereby the device is adapted for supporting and retaining the abdomen, while being at the same time possessed of the flexibility requisite to accommodate the various postures of the wearer.

The invention consists in certain novel features of the construction, and combinations and arrangements of the several parts of the improved hose supporter, whereby 25 certain important advantages are attained and the device is rendered simpler, less expensive, and otherwise better adapted and more convenient for use, all as will be hereinafter set forth.

30 The novel features of the invention will be carefully defined in the claim.

In describing the invention in detail, reference will be had to the accompanying drawings forming part of the specification, 35 wherein like characters of reference denote corresponding parts in the several views and in which—

Figure 1 is a view in perspective illustrating a hose supporter constructed in accordance with my invention; Fig. 2 is a plan view thereof; and Fig. 3 is an enlarged detail sectional view illustrating a certain detail of the invention.

The embodiment of the invention illustrated in the drawings illustrates a flattened body portion 1 made from textile material suitably secured together so as to form a flattened body adapted to be extended across the abdomen and provided at each side of 45 its upper part with an attached waist band or strip 2, said bands being adapted to encircle the waist in a manner to be herein-after described.

The upper edge 3 of the body is arranged 55 on a suitable curve to more readily conform to the figure of the wearer, and in order that

the upper part of the body or pad may be adjusted to more readily conform to the figure, there is produced within the upper part of the pad substantially centrally of 60 the width thereof, the placket 4 herein shown as approximately V-shaped and to one edge of the placket 4 are attached the spaced tabs 5 serving as anchoring means for the buckles 6 which are adapted to be 65 engaged by the straps 23, each of which having one end secured to the body portion adjacent the opposite edge of the placket, but a slight distance therefrom in order that an effective adjustment of the placket 70 may be readily obtained to meet the necessities of practice.

While it is obvious that the body portion or pad can be produced in one section it has been found of advantage to form the same 75 from a plurality of sections, preferably two as shown in the drawings, the lower edge portion of each of the adjacent sections being held in engagement by suitable stitching 7, the unattached edge portions producing the requisite placket.

At the central part of the lower edge of the pad or body 1 is produced the auxiliary pad 8 and adjacent the free corners of this auxiliary pad are attached the downwardly directed straps 9, 9 adapted to be engaged with the hose on the adjacent limb and preferably at a point adjacent the inner side thereof. These straps may be conveniently produced from elastic webbing or 90 the like, and the engagement thereof with the hose is effected by the clasps 10 at their lower ends, the upper ends of said strap being secured to the material from which the auxiliary pad 8 is produced. At the sides 95 of the body portion or pad 1 and depending therefrom are the extensions 11 terminating at a point beyond the lower extremity of the auxiliary pad 8 and to each of these extensions 11 is secured a strap 12 also preferably produced from elastic webbing and carrying clasps 13 for engagement with the hose on the adjacent limb at the front thereof. By this arrangement of the auxiliary pad 8 and the extensions 11 it will be 105 seen that said auxiliary pad and extensions are capable of movement independently one of the other whereby pull or strain on the extensions 11 will in no wise interfere with the position of the auxiliary pad 8.

Secured to each side of the body portion or pad 1 approximately centrally thereof is 110

a loop 14 preferably formed from elastic material and such loop is so formed that the pull or strain thereon will impart a transverse pull through the medium of its 5 approximately longitudinally disposed member 15 secured to the pad or body 1 adjacent the upper edge thereof while the upwardly inclined member 16 of the loop will exert an upward pull to the lower portion of the 10 body or pad 1, and it will be readily perceived from this arrangement that the pad will serve as a support for the abdomen in the nature of a shelf and that the pressure will be exerted upwardly or from beneath 15 the abdomen which as is believed to be obvious is of great advantage hygienically.

The members 15 and 16 of the loop are integral and at the junction thereof is normally positioned the clasp 17 shown in the 20 drawings as a snap clasp although this specific arrangement forms no particular part of the invention. While the exact size of the loops 14 is not material, it is essential that the upper point as at 18, shall be a distance below the points of connection as at 25 19, of the waist bands 2 with the body portion or pad 1, as it is by this arrangement that the proper pull or strain on the loops 14 is effected through the medium of the waist 30 bands or strips 2.

In practice, the pad or body portion 1 is applied as shown in Fig. 1 of the drawings and the waist bands or strips 2 are passed around the waist as at *a* and each band or 35 strip is caused to engage the clasp 17 on the side of the body portion or pad 1 opposite to the connection of the band with the body portion and said bands are then brought back to the rear of the waist as indicated 40 at *b* and tied in the usual manner as at *c*. By this arrangement it will be seen that by proper pull on the bands 2 the desired or 45 requisite strain may be given to the body portion or pad 1 and to the auxiliary pad 8 in order to effectually accomplish the functions desired.

Each of the bands 2 has secured thereto a depending member 20 capable of movement lengthwise of the band 2 and formed 50 of textile material and to the lower end of this member 20 is secured a strap 22 adapted to engage the hose at a point adjacent the rear of the limb or at any other point that may be desired. By having the members 55 capable of movement on the bands 2, it will be seen that these members 20 can be readily moved on the bands 2 to the required position after the pad has been applied, as is thought to be clearly apparent. While 60 these members 20 may be of any configuration it is particularly desired that they be

of the form shown in the drawing wherein such members are flat and having their longitudinal edges arranged on converging lines.

65

Secured to the free edge of the auxiliary pad 8, and approximately centrally of the depending straps 9, 9 I have arranged an elastic tab 24, having secured thereto a strip 25 of textile material whereby a sanitary pad or the like can be conveniently secured. And in order that such sanitary pad or other article may be conveniently carried when not in use I have provided on certain of the depending straps elastic 70 loops 26 surrounding one of such straps, herein shown as one of the straps 9, 9, adjacent opposite ends thereof, these straps being capable of operation to receive such sanitary pad or the like and to hold the 75 same thereto in a manner which is believed to be obvious.

80

From the above description of my invention, it will be seen that the improved hose supporter constructed in accordance with 85 the same is of a simple and comparatively inexpensive nature and is particularly well adapted for use by reason of the effective support afforded to the abdominal parts and in view of the fact that the pressure 90 on the abdomen is from below or upwardly and it will also be obvious from the above description that the device is susceptible of some modification without material departure from the principles and spirit of 95 the invention and for this reason I do not desire to be understood as limiting myself to the precise formation and arrangement of the several parts as herein set forth in carrying out my invention in practice.

100

Having thus described my invention, what I claim as new and desire to secure by Letters Patent is:

A device of the character described having a body portion adapted to be extended 105 across the abdomen, loops carried by the sides of the body portion, hooks held by the loops, and a waist band secured to each side of the body portion, each of said bands being adapted to engage the hook of the 110 loop at the side portion of the body opposite to the side portion to which it is secured and of such a length as to permit tying to the other of said bands after engagement with the hook.

115

In witness whereof I have hereunto signed my name, in the presence of two subscribing witnesses.

ABRAHAM ROCKOWITZ.
